UNITED STATES PATENT OFFICE.

ARNOLD F. WILLAT, OF SAN RAFAEL, CALIFORNIA.

PHONOGRAPH NEEDLE.

Application filed June 12, 1922. Serial No. 567,623.

This invention relates to improvements in phonographs needles of the type embodying in their construction extensible stylus wires or renewable playing points.

5 The primary object of this invention is to provide a relatively small, inexpensive, and reliable needle of the character described, which is adapted to fit the needle holder of an ordinary phonograph after the fashion 10 of the ordinary steel needle; which is provided with a relatively long stylus wire arranged in a novel manner upon the needle body so that one end of the wire projects below the body of the needle for engagement 15 with the sound grooves of a record, and which is provided with means for supporting said wire and for extending it, said body, wire, and means being of such construction and relative arrangement that a clear, sound 20 reproduction, free from objectionable noises is produced, and also so that the needle is not likely to become deranged or broken and may be played a great many, as, for example, 10,000 times.

25 An object of the invention is to provide a needle of the character described, which is constructed so that the wire, after being extended, cannot be withdrawn, this being provided by arrangement of the extending 30 means which operates to move the wire when moved in one direction only.

Referring to the drawings:

Figure 1 is a side elevation, partly in section, of the needle of this invention.

35 Figure 2 is a rear elevation broken away and partly in section.

Figure 3 is an enlarged top plan view of a detail of the invention.

40 Figure 4 is a fragmentary side elevation of the needle body, illustrated in detail showing the construction thereof providing for reception of the stylus needle.

Figure 5 is a fragmentary vertical sectional view taken through the needle body showing the arrangement and construction thereof prior to assembling the needle.

45 Figure 6 is a sectional view taken on the line 6—6 of Figure 1.

Figure 7 is an end view of the needle.

50 Figure 8 is a part elevation of a modified form of the needle.

Figure 9 is an end view of a detail of the form of the invention shown in Figure 8.

55 Referring particularly to the drawings, the present embodiment of the invention illustrated therein comprises a needle 1, the up-

per portion 2 of which is angularly offset and adapted to be inserted in the needle holder of a phonograph, not shown, whereas the lower portion 3 is bent back upon itself and provides the bent back portion 4. The bent back portion 4 is provided with a transverse recess or notch 5 intermediate of its ends in its inner side in which recess or notch a short cylindrical shaft 6 is mounted, said shaft having bearing engagement with the opposite face of the portion 3 of the body of the needle and projecting outwardly to one side of the body at right angles thereto. On the outer end of the shaft 6, an operating handle, preferably in the form of a star wheel 7, is mounted. A length of relatively fine wire suitable as a stylus wire, formed in a helical coil 8, is incorporated with the body, said coil being mounted upon the shaft 6 so as to surround the shaft and so that one side engages the shaft, as shown in Figure 6. One end of the coil bears against the handle 7. The wire of the coil is extended through an upwardly opening vertical slot 9 formed in the free end of the bent back portion 4 and said wire is then directed downwardly in an arc so as to extend between the shaft 6 and the portion 3, there being provided a serrated circumferential groove 10 in the shaft, 85 through which groove said wire extends. The wire extends below the shaft in engagement with the bent back portion 4 and the portion 3 and passes through a slot 11 formed by making a vertical saw cut in the joined ends of the portions 3 and 4 of the body. 90

In constructing the needle body, to adapt it for reception of the stylus wire, first, a portion of the body is bent back as described, until the body and bent back portions assume the relative positions shown in Figure 5. Next, the vertical saw cut or slot 11 is made in the lower end of the body so as to extend an equal distance into the portions 3 and 4. This saw cut is exceptionally fine, being nothing more than a slit. The slot 9 is next formed by a similar saw cut. The recess or notch 5 is then formed in the bent back portion or may be cut before the bending back of said portion. With the body thus formed, a length of wire is passed through the slot 11 so as to project beyond the lower end of the body and the portions 3 and 4 are then pressed tightly together so as 105 to assume the position shown in Figures 1, 2, 4 and 7. By applying considerable pres-

sure to these opposed parts, namely, the parts 3 and 4 of the body and to opposed sides of the slot 11, the slot is practically closed, except where the wire extends therethrough and the space between the portions 3 and 4 beneath the recess or notch 5 is practically closed except where the wire extends therebetween. The wire is then withdrawn and as this wire is relatively hard, it, after a fashion, molds or cuts a guide-way or groove therefor between the parts of the needle body which are pressed tightly together. The coil of wire is then mounted upon the shaft 6 after the shaft has been inserted in place and a part of the wire of the coil is extended in a downwardly curving arc through the slot 9 and between the portions 3 and 4 as described. This wire is further extended so that one end thereof projects through the slot 11 and beyond the lower end of the body a short distance, as shown in the drawings. By turning the handle 7 in a clock-wise direction, the shaft 6 is turned and by reason of the wire engaging in the serrated groove 10 in said shaft, said wire is advanced so as to project beyond the lower end of the needle body. I have provided the slot 11 instead of a small opening and thereby am permitted to use an exceptionally thin wire and support in a rigid manner but so as to be able to extend the wire with ease. In the use of an opening, much difficulty is experienced in providing one small enough and which will give adequate support to the wire extending therethrough.

There is provided clutch means for preventing counter-clock-wise rotation of the shaft from withdrawing the wire. This means embodies a helical spring 12 wrapped tightly around the shaft so as to closely and frictionally engage the same. One end of this coiled spring is fastened, as at 13, in the handle or wheel 7 in such manner that in turning the wheel in a clock-wise direction, the spring has a tendency to tighten and grip upon the shaft and by such frictional engagement to cause the shaft to rotate. By turning the wheel in a counter-clock-wise direction, the spring 12 is caused to unwind and loosen relative to the shaft to such an extent that it turns upon the shaft with the wheel and without imparting rotary movement to the shaft.

In Figures 8 and 9 the modified form of the invention comprises a body portion 15 formed identical with the body of the preferred form of the invention but provided with an enlarged bore 16 to receive a plug member 17. This member 17 is formed of hard steel and is provided with a V-shaped slit 18 extending longitudinally therethrough. The wire 8 lies in the slit, the plug

being so fitted in the body that the open side of the slit faces downwardly or, better, rearwardly. Thus as the weight of the sound box, etc., are brought on the projecting end of the wire, the wire is forced into the V-shaped slit and is gripped or wedged securely therein so that the projecting part thereof is held rigidly. This eliminates unnecessary vibration and objectionable noises which follow. This form of the invention does not require as much skill in the manufacture thereof and the plug fitting and other assembling can be more easily carried out than the provision of the small wire holes in the sides of the saw cut as in the end of the body of the preferred form of the invention.

I claim:—

1. A phonograph needle comprising a body portion having one end bent back upon itself, said body portion being slotted transversely through the juncture of the body and bent back portion, a stylus wire extended between the body and bent back portion and through said slotted portion, and means for moving said wire through said slotted portion. 80

2. A phonograph needle comprising a body portion having one end bent back upon itself, said body portion being provided with a slot extending transversely therethrough at the juncture of the body and bent back portion, said slot opening at the lower end 95 and certain opposite sides of the needle, a stylus wire extended between the body and bent back portion and through said slot, and means for moving said wire through said slot, said bent back portion having a slot 100 open at its free end and which receives said wire.

3. A phonograph needle embodying in its construction a body portion having an opening therein and provided with an offset upper terminal adapted to be fitted into the needle holder of an ordinary phonograph, a stylus wire movable through the opening in said body portion and means associated with the wire and body portion for advancing 110 said wire through said opening. 105

4. A phonograph needle embodying in its construction a body portion adapted to have its upper end fitted in the needle holder of an ordinary phonograph and bent back upon itself at its lower end, the bent back portion being slotted transversely at the lower extremity and on opposite sides thereof, a stylus wire extending through said slit and means associated with the body portion and 120 stylus wire for moving the wire relative to the body portion. 115
